UNITED STATES PATENT OFFICE

ELMER M. WANGEN, OF DULUTH, MINNESOTA

LINE READING DEVICE

Application filed July 18, 1932. Serial No. 623,252.

The invention relates to devices for facilitating copying by typists and has reference more particularly to a line reader which will render visible a single line of the copy until 5 adjusted to bring into view the next line.

An object of the invention is to provide a device that will be noiseless when line spacing, that can be readily suspended from a suitable support, and one that will take up 10 very little space when in use or when stored.

Another object is the provision of a copy holder and line reader that can be operated for spacing purposes simultaneously with the typewriter, thus saving valuable time 15 and which can be located in the most desirable position for the typist.

With these and various other objects in view, the invention may consist of certain novel features of construction and operation, 20 as will be more fully described and particularly pointed out in the specification, drawing and claims appended hereto.

In the drawing which illustrates an embodiment of the device and wherein like reference characters are used to designate like 25 parts—

Figure 1 is a front elevational view of the device of the present invention shown supported from a card and envelope carriage;

30 Figure 2 is an end view of the device taken on line 2—2 of Figure 1;

Figure 3 is a transverse sectional view taken on line 3—3 of Figure 1;

35 Figure 4 is a fragmentary sectional view showing the construction of one end of the main roller, and

Figure 5 is a fragmentary sectional view showing a modified construction of the other end of the roller.

40 The embodiment of the device shown in the drawing consists essentially of a sectional shield having an upper section 10 of arcuate contour as shown in Figure 3 and a lower section 11 also of arcuate contour, and having 45 a curved depending lip 12. The sections are pivotally secured together at their adjacent edges by spaced co-operating lugs 13, formed on the sections respectively, which lugs are connected by the pivot shaft 14. 50 The pivoting means for the sections are lo-

cated at each end of the shield and have associated therewith a coil spring 15 encircling the shaft 14, one end of the spring engaging section 10, while the other end engages section 11, maintaining them in desired position, as will be more clearly understood as the description proceeds.

55 Section 10 has formed integral therewith supporting members 16 having hook portions 17 on their upper ends for engaging with and supporting the section and thus the line reader from a card and envelope carriage designated in its entirety 18. The carriage provides an adjustable support that can be raised and lowered and moved forward and 60 rearward with respect to the operator so that the line reader is also adjustable therewith. The card and envelope carriage is disclosed as it comprises the preferred form of 65 support for the present line reader, but it is clear that any other support can be substituted therefor without altering the efficiency 70 of the device.

The upper section 10, in addition to the integral member 16, has suitably secured at its ends semi-circular portions 20 which provide journalling means for a main roller 21 positioned within the shield. The roller is formed of a cylindrical steel tube 22 having 75 positioned thereon a covering 23 of rubber or other suitable material and receiving at its respective ends metal plugs 24 provided with integral circular portions 25 completing the 80 ends of the roller. One of the metal plugs 24 is provided with an integral stud shaft 26, while shaft 27 is threaded to the other plug, so that the same can be detached from the roller without requiring removal of the plug. Fitted 85 to reduced portions on the shafts 26 and 27 are discs 28 having knurled peripheries so that the operator by grasping the discs and 90 rotating the same can impart the desired rotation to the roller. The lower section 11 carries a plurality of spaced rollers 30 formed of rubber or other suitable composition and which extend a slight distance inwardly of 95 the arcuate section so that the same is spaced from roller 21 a distance equal to that of the upper section, when the rollers are in engagement. The operative position of the vari-

ous parts of the present device is thus shown in Figure 3, where the lower section is horizontally urged by the coil springs 15 inwardly toward the main roller 21 so that the small rollers carried by the lower section engage with the main roller.

A copy is located within the device by withdrawing the lower section where the rollers 30 are lifted out of contact with the main roller 21 and inserting the copy between the main roller and the upper section 10. The lower section is then released so that the copy is located between the main and small rollers and by rotating the main roller through discs 28 the position of the copy can be adjusted. For rendering visible to the typist or operator a single line only of the copy the inner edges of the sections are cut away forming an elongated slot 32 of a length determined by the distance between the pivot means on the ends of the shield and of a width slightly greater than that of a type-written line. Since only a small portion of the copy is located between the shield and main roller the position of the same can be readily adjusted by the operator to align the written matter thereon with the slot 32. Line spacing of the copy, after it has been levelled with respect to slot 32, is taken care of by rotating the disc 28, which in turn rotates the main roller, and as the copy is gripped between the rollers the same is caused to move as desired.

I claim:

1. In a device of the character described, in combination, a sectional shield, means pivotally securing the sections of the shield together at the ends, an elongated slot in the shield, and a roller rotatably supported from one section of the shield.

2. In a device of the character described, in combination, a sectional shield, means pivotally securing the sections of the shield together at the ends, an elongated slot in the shield, end portions secured to one section and journaling a roller, and rollers mounted in the other section for contacting the first named roller.

3. In a device of the character described, in combination, a shield having an upper and lower section, means pivotally securing the sections together, an elongated slot in the shield, said upper section having supporting means for the shield and journaling a main roller, and said lower section carrying a plurality of rollers for contacting the main roller.

4. In a device of the character described, in combination, a shield having an upper and lower section, said sections being pivotally secured together, the inner edges of the sections being cut away providing an elongated slot, means on the upper section for journaling a main roller, and a plurality of

smaller rollers carried by the lower section for contacting the main roller.

5. A line reading device, including arcuate sections pivoted together forming a shield, a main roller extending substantially the length of the shield and being journalled to one section, cut away portions in the sections at their inner edges forming an elongated slot, and said other section having means contacting the roller.

6. A line reading device, including arcuate sections pivoted together forming a shield, one section being provided with supporting members for the shield, a main roller extending substantially the length of the shield and being journalled to said section, cut away portions in the sections at their inner edges forming an elongated slot, and the other section carrying rollers for contacting the main roller.

7. A line reading device including arcuate sections pivoted together forming a shield, one section being provided with supporting members for the shield, a main roller extending substantially the length of the shield and being journalled to said section, cut away portions in the sections at their inner edges forming an elongated slot, the other section carrying rollers for contacting the main roller, and resilient means holding said other section with the rollers in engagement.

8. A line reading device including arcuate sections pivoted together forming a shield, the upper section being provided with supporting members for the shield, a main roller extending substantially the length of the shield and being journalled to said section, cut away portions in the sections at their inner edges forming an elongated slot, the lower section carrying rollers for contacting the main roller, and resilient means holding the lower section with the rollers in engagement.

9. A line reading device including an elongated shield of arcuate contour transversely of the shield, supporting means therefor, a roller extending substantially the length of the shield and being journalled in end portions on the shield, a plurality of spaced rollers carried thereby and having contact with the main roller, and a slot extending longitudinally of the shield.

Signed at Duluth, Minn., this 7th day of July, 1932.

ELMER M. WANGEN.
